WIRES STITCHING MACHINE

Filed Jan. 13, 1931

UNITED STATES PATENT OFFICE

JOHN IRVING NASMITH, OF ELTHAM, ENGLAND, ASSIGNOR TO VICKERS-ARMSTRONGS
LIMITED, OF WESTMINSTER, ENGLAND, A BRITISH COMPANY

WIRE STITCHING MACHINE

Application filed January 13, 1931, Serial No. 508,456, and in Great Britain December 1, 1930.

This invention relates to wire stitching machines. Such machines are usually provided with suitably operated members for the purpose of feeding a length of wire, for bending it into a staple and for driving the staple thus formed into the work to be stitched. The members are afforded their correct timed motions by means of cams or other means driven from the driving shaft of the machine. By suitable adjustment of the various motions of the members the correct actuation thereof according to a predetermined timed cycle is obtained. The present invention has exclusive reference to wire stitching machines in which the motion for feeding the wire for the stitches or staples is initially derived from a revolving feed cam. The feed cam is adapted to actuate a two armed feed lever which imparts proper motion to mechanism which performs the function of feeding a length of wire for the stitch or staple. After the length of wire has been fed, a member known as the former bends the length of wire in conjunction with another member (generally referred to as the "loop bar") into the form of a staple and supports the formed staple whilst being driven into the work by the action of a member known as the driver.

The object of the present invention is to improve the mechanical details of this type of machine and to overcome certain defects common to machines of this type at present in use.

The invention consists in a wire stitching machine comprising a two armed feed lever for feeding a length of wire, a revolving feed cam for operating said feed lever, a former for forming the length of wire into a staple, a cam for operating said former and a driver for driving the staple thus formed into the work, both arms of said feed lever and the said cam lying and moving in the same plane as that of the driver and former. The driver is actuated by means of a link connected to the feed cam and is preferably arranged so that the crank pin or the pin upon which the link is pivoted is totally enclosed and contained in the feed cam. The driver is thus afforded a vertical reciprocating motion of suitable amplitude for the purpose of driv-

ing the staple into the work. The feed lever is oscillated by means of the feed cam which as above mentioned actuates the driver by means of the aforesaid link and the former is given its timed motion by means of a cam 55 the path of which preferably lies entirely external to the feed cam. By such a disposition of the parts the twisting forces set up in actuating the members is reduced to a minimum. 60

In order that the said invention may be clearly understood and readily carried into effect the same will now be more fully described with reference to the accompanying drawing in which:—

Figure 1 is a front elevation of one end of a wire stitching machine with the front cover of the machine removed so as to expose the mechanism according to the invention;

Figure 2 is a vertical sectional elevation 70 taken along the line 2—2 of Figure 1, and

Figure 3 is a horizontal section taken along the line 3—3 of Figure 1.

The driving shaft 4 of the machine is carried at the end of the machine shown by 75 means of a suitable bearing 5 mounted in the frame 6. Rigidly secured to the end of the driving shaft is a cam plate 7 which is provided with a cam path 8 with which co-operates a roller 9 which is attached to and actuates the former 10. The shaft 4 also carries the feed cam 11 which may be separate from the cam plate 7 or as shown it may be formed integrally therewith. The driver 12 is adapted to reciprocate in guides provided on the former 10 and for the purpose of actuating the driver 12 a link 13 is provided connected to the upper end of the driver 12 and to the feed cam 11. The link 13 is provided with a crank pin 14 which is totally enclosed and contained in the feed cam 11. The front face of the feed cam 11 is arranged immediately adjacent to the inner face of the link 13 and lies in the plane containing the front face 80 of the driver 12. The feed lever 14 pivoted at 15 upon the frame of the machine operates at one end against the periphery or working face of the feed cam 11. The working face of the feed cam is as shown arranged vertically above the driver and former in order 85

85

100

to permit the feed lever 14 to be arranged in the same plane as the former and driver as shown more clearly in Figure 3. It will be observed that the feed cam 11 is shown as an open cam and the feed lever is maintained in contact with the working face of the cam by means of a spring 16. If desired, however, the feed cam may be formed as a double sided cam so as to operate the feed lever positively in both directions. The former cam groove 8 is provided in the cam plate 7 immediately behind the feed cam 11 and thus necessarily is such that the cam path 8 is entirely exterior to the periphery of the feed cam 11.

Due to the above described arrangement it will be observed from Figure 3 that the three operated members, namely the feed lever, the former and driver may be arranged in a single plane or in other words the two arms of the feed lever 14 may be so arranged that both of them lie in the same plane as that of the driver and former.

What I claim and desire to secure by Letters Patent of the United States is:

1. A wire stitching machine comprising a two armed feed lever for feeding a length of wire, a revolving cam for operating said feed lever, a former for forming the length of wire into a staple, a cam for operating said former, and a driver for driving the staple thus formed into the work, both arms of said feed lever and the said cam lying and moving in the same plane as that of the driver and former.

2. A wire stitching machine comprising a two armed feed lever for feeding a length of wire, a former for forming the length of wire into a staple, a cam for operating said former, and a driver for driving the staple thus formed into the work, both arms of said feed lever being arranged so that they lie and move in the same plane as that of the driver and former, and a revolving cam for operating the feed lever disposed vertically above and in the same plane as the driver and former.

3. A wire stitching machine comprising means for feeding a length of wire, a former for forming the length of wire into a staple, a cam for operating said former, and a driver for driving the staple thus formed into the work, a two armed feed lever, a cam for actuating the feed lever, said feed lever and said cam being disposed in the same plane as that of the driver and former, and a link connected to said cam and to the driver for actuating the latter.

4. A wire stitching machine as in claim 3, wherein the link is connected to said cam by means of a crank pin which is completely enclosed or contained in the cam.

5. A wire stitching machine comprising a two armed feed lever for feeding a length of wire, a cam for operating said feed lever,

a former for forming the length of wire into a staple and a driver for driving the staple thus formed into the work, said feed lever and the said cam being disposed in the same plane as the driver and former, a cam for actuating the former, said cam for actuating the feed lever being situated in front of said cam which actuates the former.

6. A wire stitching machine comprising a two armed feed lever for feeding a length of wire, a cam for operating said feed lever, a former for forming the length of wire into a staple and a driver for driving the staple thus formed into the work, both arms of said lever lying and moving in the same plane as that of the driver and former, a cam for actuating the former, said cam for actuating the feed lever being situated in front of the cam which actuates the former.

7. A wire stitching machine as in claim 5, wherein the cam which actuates the former is situated entirely external to the feed cam.

8. A wire stitching machine as in claim 6, wherein the cam which actuates the former is situated entirely external to the feed cam.

9. A wire stitching machine comprising a two armed lever for feeding a length of wire, a former for forming the length of wire into a staple and a driver for driving the staple thus formed into the work, both arms of said feed lever lying and moving in the same plane as that of the driver and former, a cam for actuating the feed lever, a link connected to said cam and to the driver for actuating the latter, said link being connected to said cam by means of a crank pin which is completely enclosed or contained in the cam.

10. A wire stitching machine comprising a two armed lever for feeding a length of wire, a former for forming the length of wire into a staple and a driver for driving the staple thus formed into the work, both arms of said feed lever lying and moving in the same plane as that of the driver and former, a cam for actuating the feed lever disposed vertically above the driver and former, a link connected to said cam and to the driver for actuating the latter, said link being connected to said cam by means of a crank pin which is completely enclosed or contained in the cam.

JOHN IRVING NASMITH.
